232,171

TIRE OR SIMILAR ARTICLE

Gernot Arendt, Traiskirchen, Austria, assignor to Firma
Deutsche Semperit Gummiwerk G.m.b.H., Munich,
Germany

Filed July 29, 1971, Ser. No. 167,539

Claims priority, application Germany Feb. 10, 1971;
Mar. 26, 1971

Term of patent 14 years

Int. Cl. D12—15

U.S. Cl. D12—142

FIG. 1

Des. 232,171

PAGE 2

FIG. 2

FIG. 3

FIG. 4

FIG. 1 is a perspective view of a tire or similar article showing my new design;

FIG. 2 is a perspective view of a second modified embodiment of the tire illustrated in FIG. 1;

FIG. 3 is a perspective view of a third modified embodiment of the tire illustrated in FIG. 1;

FIG. 4 is a perspective view of a fourth modified embodiment of the tire illustrated in FIG. 1;

FIG. 5 is a perspective view of a third embodiment of tire incorporating my invention;

FIG. 6 is a sectional view of the tire depicted in FIG. 5, taken substantially along the line III-III;

FIG. 7 is a perspective view of a fourth embodiment of tire incorporating my invention; and

FIG. 8 is a sectional view of the tire depicted in FIG. 7, taken substantially along the line IV-IV thereof.

I claim:

The ornamental design for tire or a similar article, as shown and described.
